(57) **CLAIM**

We claim the ornamental design for a canister for dispensing dry foods, as shown and described.

DESCRIPTION

FIG. 1 is a perspective view of a canister for dispensing dry foods of the present invention;

FIG. 2 is a front plan view of the canister for dispensing dry foods of the present invention;

FIG. 3 is a first side plan view of the canister for dispensing dry foods of the present invention;

FIG. 4 is a back plan view of the canister for dispensing dry foods of the present invention;

FIG. 5 is a second side plan view of the canister for dispensing dry foods of the present invention;

FIG. 6 is a bottom plan view of the canister for dispensing dry foods of the present invention; and,

FIG. 7 is a top plan view of the canister for dispensing dry foods of the present invention.

Features shown in broken lines of the drawings are not part of the claim.
